UNITED STATES PATENT OFFICE.

OSCAR PAUL LOCHMANN, OF GOHLIS, NEAR LEIPSIC, SAXONY, GERMANY.

MUSICAL BOX.

SPECIFICATION forming part of Letters Patent No. 374,127, dated November 29, 1887.

Application filed September 8, 1887. Serial No. 249,132. (No model.)

To all whom it may concern:

Be it known that I, OSCAR PAUL LOCHMANN, a subject of the King of Prussia, residing at Gohlis, near Leipsic, in the Kingdom of Saxony, German Empire, have invented new and useful Improvements in Musical Boxes, of which the following is a specification.

This invention has for its object to provide novel means for rotating the circular note-plate of a music-box; and to such end the invention consists in the features of construction and combination of devices, hereinafter described and claimed.

Figure 1 of the accompanying drawings is a plan view of the musical box. Fig. 2 shows a section on *k y* of Fig. 1. Figs. 3 and 4 show the arrangement of the driving mechanism on a larger scale than Figs. 1 and 2. Figs. 5, 6, and 7 are modifications of the driving con-

20 trivance shown in Figs. 3 and 4.

The base-plate *a* has in its center a nipple, *b*, cast in one piece with it and provided with a threaded bolt, *c*. The nipple *b* serves to receive the note-plate *p*, secured by a nut, *d*.

25 The note plate extends through a lateral slot in a nipple, *e*, which is also formed in one with the base-plate *a*. The nipple *e* is vertically bored out to receive the crank-shaft *f*, which is formed as a driving-shaft, and for that purpose provided with teeth engaging teeth arranged on the circumference of the note-plate, so that by turning the crank the note-plate is directly rotated by the crank-shaft.

30 Fig. 5 shows a modification of the above-described construction. The note-plate is not conducted in a slot on the nipple *e*, but on the upper surface of the nipple. The shaft *f* is in this case provided with a collar, *m*, lying with an elastic washer, *n*, upon the note-plate *p*. In 35 turning the crank a pressure is exerted on the shaft *f*, which pressure is transmitted by the elastic washer to the note-plate *p*, so that the latter is conducted between the collar *m* and the nipple *e*. Any vibration of the note-plate

is avoided by this arrangement, which, moreover, has the advantage that the note-plate can more easily be put in and changed, as after the removal of the crank the note-plate does not find any resistance on its periphery.

45 Figs. 6 and 7 show another modification. The teeth of the note-plate *p*, as well as of the shaft *f*, are here dispensed with. The rotation of the plate *p* is obtained here by friction, the crank-shaft *f* being provided with a collar, *m*, which, by means of a washer, *n*, of leather or of any other suitable material, presses on the note-plate *p* and puts it in rotation. In order to prevent the note-plate *p* from being pressed too tightly against the upper surface of the nipple *e*, a small wheel, *r*, is arranged in 55 the nipple on which the note-plate slides.

I claim—

1. The combination, with the circular note-plate of a music-box, of a base-plate, a vertical tubular nipple, and a rotating crank shaft journaled vertically in said nipple, and having means to engage and rotate the note-plate, substantially as described.

2. The combination, in a music-box, of a base-plate having nipples *b* and *e*, the circular note-plate *p*, centrally mounted on one nipple, and a crank-shaft journaled within the open nipple and engaging the note-plate to rotate the latter, substantially as described.

3. The combination of the base-plate, the tubular nipple having a lateral slot, the circular note-plate extending into said slot, and the rotating vertical crank-shaft journaled in the nipple and engaging the note-plate to rotate the same, substantially as described.

40 In testimony whereof I have signed my name to this specification in the presence of two subscribing witnesses.

OSCAR PAUL LOCHMANN.

Witnesses:

CARL BORNGRAEBER,
HUGO TELLER.
